UNITED STATES PATENT OFFICE.

GEORGE GARDNER, OF WOOD'S STATION, OHIO.

JOINT FOR RAILROAD-SWITCHES.

SPECIFICATION forming part of Letters Patent No. 236,152, dated January 4, 1881.

Application filed August 16, 1880. (No model.)

To all whom it may concern:

Be it known that I, GEORGE GARDNER, of Wood's Station, in the county of Butler and State of Ohio, have invented a new and useful 5 Improvement in Joints for Railroad-Switches, which improvement is fully set forth in the following specification and accompanying drawings, in which—

Figure 1 is a plan view of tracks provided 10 with my hinged joints, and Fig. 2 is a perspective elevation of the joint itself.

The object of this invention is to provide a 15 hinged joint at the point where the rails of the main track and side track cross each other, so as to dispense with the dangerous frogs now in use.

In order to diminish the necessary throw of 20 the swinging ends of the rails and to diminish the width of the rails to be moved, the four rails of the two main tracks are 25 converged into three rails, and similarly the eight rails of the two main and two side tracks are converged into five rails.

In the accompanying drawings, A represents 30 the rails of the main track, bound together at suitable distances by means of the tie-rods A', as in switches of this character, the meeting ends of said rails resting upon a metal plate, a, which rests on the large middle wooden tie, b.

Referring to Fig. 2, it will be noticed that 35 the branch rails B are tapered, so that when placed side by side, (with their opposite ends apart from each other,) the two together are the same width as the single rail A, against which they abut.

Within the hollows of the T-rail, on each side, are secured, by bolts D', the strap or part of a hinge, D, having at the end a horizontal slot, E, into which the tongue H of the strap G is placed. The strap G is secured by 40 bolts I to the single rail A, and a bolt, F, unites the two parts D G of the hinge.

The rails, on being moved from side to side, 45 as indicated by the dotted lines, will bend sufficiently from the hinged joint to the end; or, if desired, a slotted aperture for the reception of the bolt F may be made in the tongue H of the hinge, so as to allow sufficient play 50 to give a lateral movement to the opposite end of the rail.

Various modifications of the hinge portion can be made without departing from the spirit

of my invention; but my object is to permanently secure the two ends of the branch rails 55 C, so that no matter in which direction the rail A may be turned the point usually occupied by the old-fashioned frog will be left as safe as any other part of the track. Further than this, the great objection to having long rails 60 like A unsupported is provided for from the fact that, the hinges being on both sides of the rail, there will be no liability of the rail turning over by the lateral thrust of the car-wheels, as is frequently the case.

In Fig. 1 I show the disposition of the main and side tracks as used with my improved switch-joint. The dotted lines show the positions of the rails A when switched from one track to the other. This is accomplished by 70 means of the lever K, pivoted to the tie b, and hinged on each side of the tie to the tie-rods J, fastened to the rails A.

The two main tracks are united at x in such a manner that the middle rail forms one of the 75 rails for each track, and since each rail, where joined to the converging lines, is provided with the hinged joint, it can easily be moved, will be perfectly firm and upright, and will leave no opening between the rails.

The exterior diverging rails represent the 80 ends of side tracks; but, if desired, an additional track or tracks can be added at each end of the switch.

Having described my invention, what I 85 claim as new, and desire to secure by Letters Patent, is—

1. The tapered converging rails B, secured together permanently by means of bolts or otherwise, and hinged to the movable rail 90 A by means of the loose hinges D G on each side of said rails, substantially as herein set forth.

2. The hinged switch-joint herein described, which consists in having the abutting ends of 95 switch-rails joined by means of loose hinges D G, substantially as and for the purpose set forth.

In testimony that I claim the foregoing I have hereunto set my hand this 10th day of 100 August, A. D. 1880, in the presence of witnesses.

GEORGE GARDNER.

Witnesses:

ISAAC ROYERS,
CHAS. P. KRAMER.
